CLAIM

The ornamental design for a cable safety climb adapter bracket, as shown and described.

DESCRIPTION

FIG. 1 is a front elevation view of a cable safety climb adapter bracket showing my new design;

FIG. 2 is a rear elevation view of the cable safety climb adapter bracket;

FIG. 3 is a side elevation view of the cable safety climb adapter bracket, it being understood that the opposite side elevation view is a mirror image thereof;

FIG. 4 is a top plan view of the cable safety climb adapter bracket; and,

FIG. 5 is a bottom plan view of the cable safety climb adapter bracket.

The elements shown in broken lines are for illustrative purposes only and form no part of the claimed design.
